UNITED STATES PATENT OFFICE.

MARTIN J. O'CONNOR, OF OGDEN, UTAH.

CYLINDER LOCK.

Application filed May 16, 1922. Serial No. 561,270.

To all whom it may concern:

Be it known that I, MARTIN J. O'CONNOR, a citizen of the United States, residing at Ogden, in the county of Weber and State 5 of Utah, have invented certain new and useful Improvements in Cylinder Locks; and I do hereby declare the following to be a full, clear, and exact description of the invention, such as will enable others skilled 10 in the art to which it appertains to make and use the same.

My invention relates to cylinder locks and more particularly to locks of this type which are adaptable for fitting to doors of 15 various thicknesses, and the object of my invention is to provide such a lock with improved and simple means whereby the length of the lock may be adjusted to appropriate position and automatically locked 20 in such position after the cylinder has been screwed into the lock case, such means forming an integral part of the lock elements.

In the drawings, Figure 1 is a view in side elevation showing the cylinder and 25 tumbler casing in extended position, parts being shown broken away. Figure 2 shows the cylinder and casing completely telescoped. Figure 3 is a top plan view. Figures 4 and 5 are cross sectional views on 30 lines 4—4 and 5—5, respectively, Figure 3. Figure 6 is a perspective view showing the cylinder casing separated.

My improved lock includes a face plate 1 to the rear of which is secured the tumbler 35 casing 2 superposed on which are ribs 3 and 4 and 5 which serve as supports for a cylinder 6. Seated upon the upper side of each of the ribs 3 and 5 is a spring dog 7 the upwardly extending portion of which 40 is apertured to receive a notched pin 8 projecting forwardly from the closed end 9 of the cylinder. The latter has longitudinally extending cut out portions 10 through which access may be had to press 45 the spring dog so as to disengage it from the notches of the pin in order to withdraw the tumbler casing from the cylinder. To prevent the complete disengagement of these parts I provide a cotter 12 at the end 50 of each pin 8.

The tumbler casing 2 being telescoped within the cylinder 6, as shown in Figure

2, pressure on the spring dogs 7 to disengage them from their respective pins 8 will permit relative extension between the cylinder 55 and casing, as shown in Figure 3. In this extended position, the cylinder is screwed into the lock and the face plate 1 with the tumbler casing is then pushed inwardly until up to the face of the door to which it 60 is attached, the spring dogs 7 freely riding over the notches of the pins 8 in this inward movement. When the parts are so telescoped they are automatically locked and 65 cannot be separated while in position on the 65 door.

I claim as my invention:

1. In a lock including a tumbler casing and a telescoping cylinder therefor, said cylinder being adapted to be screwed into a 70 lock case, means in part carried by said tumbler casing and in part by said cylinder for automatically locking said casing and said cylinder such means permitting longitudinal movement in one direction only between said casing and cylinder. 75

2. In a lock including a tumbler casing and a telescoping cylinder therefor, a detent on said casing and a notched member carried by said cylinder with which said 80 detent engages to permit longitudinal movement in one direction only between said casing and cylinder.

3. In a lock including a tumbler casing and a telescoping cylinder therefor, a pair 85 of spring dogs superposed on said casing, and notched members carried by said cylinder with which said spring dogs engage to permit longitudinal movement in one direction only between said casing and cylinder. 90

4. In a lock including a tumbler casing having superposed ribs thereon and a telescoping cylinder for said casing supported by said ribs and having a closed end, spring dogs mounted on a plurality of said ribs, and a pair of notched pins projecting forwardly from the closed end of said cylinder with which said spring dogs engage to permit longitudinal movement in one direction only between said casing and cylinder. 95

5. In a lock including a tumbler casing and a telescoping cylinder therefor, said cylinder being closed at one end and having longitudinal cut outs, a notched pin projecting 100

from the closed end of said cylinder in line with each of said cut outs, a pair of spring pressed dogs superposed on said tumbler casing adapted to interlock with said notched pins to permit longitudinal movement in one direction only between said casing and cylinder in the fitting of the lock,

said longitudinal cut-outs permitting access to said dogs to manually disengage them from said pins to separate the casing and cylinder preparatory to fitting the lock.

In testimony whereof I have signed this specification.

MARTIN J. O'CONNOR.
